UNITED STATES PATENT OFFICE

JOHN G. BERGDOLL, OF YORK, PENNSYLVANIA, ASSIGNOR TO YORK ICE MACHINERY CORPORATION, OF YORK, PENNSYLVANIA, A CORPORATION OF DELAWARE

REFRIGERATION

Application filed July 21, 1928. Serial No. 294,418.

This invention relates to refrigerating systems and particularly to means for operating the condenser under super-pressure when the refrigerant is discharged at or near the critical temperature.

While the invention is not limited to any particular refrigerant, but is useful with any refrigerant condensed within the temperature ranges just mentioned, it has particular commercial utility in connection with carbon-dioxide machines and will be discussed on the basis of the properties of carbon-dioxide. This discussion, however, is merely for illustrative purposes, and no necessary limitation to carbon-dioxide is implied except to the extent expressly stated.

To secure the best refrigerating effect the lowest practicable temperature of the refrigerant leaving the condenser should always be obtained. Space is always a consideration, and where the temperature and amount of available cooling water are such as to enter as controlling factors, the best results can be accomplished by using a counterflow condenser, because in this way it is possible to discharge the condensed refrigerant with the minimum temperature difference from the entering cooling water.

The essence of the present invention resides in the increase of the heat transfer by increasing the pressure under which condensation occurs in controlled relation to the temperature of the refrigerant leaving the condenser. The importance of improvement in this respect will be apparent from the following:

The refrigerating effect of one pound of carbon-dioxide expanded from a saturated pressure condition into an evaporator decreases as the temperature of the liquid increases. This is true regardless of evaporator temperature for the refrigerating effect varies only 2% (approximately) when evaporator temperature varies from -20° F. to +35° F. Therefore, if we disregard evap-

orator temperature which will in practice be between the limits stated, the values will run about as follows:

81 B. T. U's for 60° liquid at 750 pounds.
73 B. T. U's for 70° liquid at 850 pounds.
64 B. T. U's for 80° liquid at 965 pounds.
57 B. T. U's for 85° liquid at 1030 pounds.
42 B. T. U's for 88.4° liquid at 1075 pounds.
The critical temperature is 88.4°.

Above the critical temperature liquefaction does not occur and the refrigerating effect continues to decrease. If, however, condenser pressures are increased above saturation pressures the refrigerating effect is markedly increased, and the increase is even greater above than below the critical temperature. The following are computed values:

65 B. T. U's for 80° liquid at 1000 pounds.
62 B. T. U's for 85° liquid at 1100 pounds.
60 B. T. U's for 88.4° liquid at 1170 pounds.
59 B. T. U's for 90° from condenser at 1215 pounds.
57 B. T. U's for 95° from condenser at 1330 pounds.

Of course, the increase in pressure entails an increased power input and an increased cooling water flow, but it is possible to develop by experiment tables as just outlined giving the super-pressure for best effect.

The present invention contemplates the control of condenser pressure in accordance with the temperature of refrigerant leaving the condenser. This regulation may be direct, that is, the automatic regulation may be performed in response to the temperature of the refrigerant leaving the condenser. Ordinarily, however, such an arrangement results in a structure not particularly desirable for commercial installations, and an approximately identical result can be secured by regulating according to the temperature of the cooling water leaving the condenser, or even according to the temperature of the entering cooling water.

Assuming an approximately constant refrigerating load the temperature of the condensed refrigerant will vary in a direct relation with the temperature of the cooling water.

at one or the other point. The essential thing is that the controlling temperature shall be either the temperature of the condensate or a temperature which is a function thereof, so

5 that the regulating action shall be in effect a regulation in response to condenser temperature.

In the accompanying drawings several arrangements embodying automatic control are 10 illustrated and an opportunity has been taken to show the application of the invention to systems in which the compression cycles vary slightly, the purpose being to bring out the 15 general applicability of the invention regardless of the specific details of the refrigerating cycle with which it is used.

In the drawings,—

Fig. 1 is a vertical axial section of the condenser discharge regulating valve such as 20 may be used in the practice of the invention.

Fig. 2 is a diagrammatic view of a system including the valve of Fig. 1, showing a simple compressor and an ordinary receiver suction trap.

25 Fig. 3 is a fragmentary view showing how the regulating valve might be included in Fig. 2 in such a way as to be subject to the temperature of the discharging condensate.

Fig. 4 is a diagram somewhat similar to 30 Fig. 2 and showing the regulating valve controlled by the temperature of the discharging condensing water. In this view a slightly different system is illustrated in which the feed of liquid refrigerant to the receiver suction trap is controlled by a float valve in an intermediate suction trap. In such a system a compressor capable of maintaining simultaneously two different suction pressures is used.

40 Referring first to Fig. 1, 11 represents a valve body having an inlet passage 12 and a discharge passage 13. The discharge passage leads from the bore of a valve seat bushing 14 which is threaded into a boss 15 cast integral with the body 11. The body 11 is open at its upper side, the opening being closed by a cap 16 which seats on a gasket 17, and which is held in place by machine screws 18. The cap 16 guides a vertically movable valve

45 stem 19 which is vertically slidable in the bushing 14 and acts as a valve therein by virtue of an axial port 21 having one or more lateral ports 22 (four being indicated). In the upper position of the stem 19 these ports

50 22 register with an annular groove 23 which forms a continuation of the passage 13. As the valve stem 19 moves downward from its upper position the lateral ports 22 are progressively blanked or throttled to restrict the

55 flow by way of 21, 22, 23 and 13. A flexible metallic bellows 24 is used at this point to prevent leakage. The dimensions of the stem 19 and bellows 24 are so chosen that condenser pressure acting on the stem and bellows ex-

60 65 ercises a properly proportioned force, de-

pendent on condenser pressure and opposed to the force exerted by bellows 29 in response to condenser temperature as hereinafter explained.

Supported on the body 11 are upright rods or frame members 25, conveniently four in number, which carry at their upper end a frame or yoke 26. This supports the head 27 of a pressure motor which is the thermally responsive element of the device. This motor may assume various different forms, but is here shown as including a head 28 and metallic bellows 29 which make tight joints with the heads 27 and 28. The head 27 has an upwardly projecting nipple 31 which extends through a hole in the center of the frame member 26 and above such frame member receives a nut 32 which locks the parts in assembled relation. The member 31 is provided with an axial port 33 which leads to a threaded counterbore 34.

In the embodiments of Figs. 2 and 4, the passage 33 is closed by a plug threaded into the counterbore 34. In the embodiment of Fig. 3 the threaded counterbore 34 serves as a connection for the pressure conducting pipe, as will hereinafter be made plain. Upward movement of the head 28 is limited by a thrust member 35 carried thereby. The head 28 acts in thrust against the valve stem 19 which has a shouldered reduced end 36 entering a socket in a portion of the head 28. A spring 37 acts in thrust between the head 28 and a seat 38. This seat may be adjusted by turning the adjusting nut 39, which is threaded on the tube 41. The tube 41 is fixed in the head 16 and surrounds the stem 19.

It will be understood that the bellows 29 contains between the heads 27 and 28 an expansible fluid, which develops a variable pressure serving to force the stem 19 downward in a valve closing direction.

Where regulation is to be had by means of the condensing water, as in Figs. 2 and 4, the water is brought into contact with the outside of the bellows 29 by passing it through a cup or jacket in which the bellows are mounted. This cup is shown at 42. It is threaded upon a downward extending nipple portion of the lower head 28 and seals against a gasket 43. The cup thus partakes of the vertical movements of the valve stem 19 and head 28, the cooling water being conducted to and from the cup by flexible connections 44 and 45. In certain arrangements of the device the cup 42 may be omitted, as herein-after explained.

Turning now to Fig. 2, an evaporator 51 is shown as submerged in brine in a tank 52. The lower end of the evaporator 51 is connected to the bottom of receiver suction trap 53 and the upper end is connected to the upper side of the receiver suction trap 53, this being a familiar arrangement to maintain the evaporator 51 flooded, and to return to the

evaporator any unevaporated liquid refrigerant which may discharge from the top of the evaporator.

- 5 The suction connection 54 leads to the compressor 55 which discharges through the high pressure gas line 56 to the upper end of a double pipe condenser. This condenser is made up of internal water conducting pipe 57 and a surrounding pipe 58 or larger size. 10 The uncondensed high pressure gas entering by the pipe 56 flows through the interval between the pipes 57 and 58 in counter-flow relation to the water, and the cooled or condensed refrigerant discharges from the condenser through the high pressure liquid line 59.

- 15 Pipe 59 is connected to the inlet passage 12 in the housing 11. The discharge passage 13 of the housing 11 is connected by the low pressure liquid line 61 to the receiver suction trap 53. As has been stated, the cooling water flows in counterflow relatively to the refrigerant and in the example illustrated in Fig. 2 the entering water flows first through 20 the cup 42, that is, a supply pipe 62 leads through the flexible connection 45 to the cup 42 while the other flexible connection, 44, is connected to the pipe 62 which connects with the pipe 57 at the lower end of the condenser. 25 In such case the cup 42 must be closed at its top by bellows 40 if the cup is below the level of cooling water discharge. Water discharging from the pipe 57 at the upper end of the condenser, may flow to waste or be 30 otherwise disposed of.

- 35 As explained, and as illustrated in Fig. 4, the water connections might be interchanged so that the discharging water instead of the entering water flows through the cup 42. The prime purpose is to control the throttling 40 action of the valve member according to condenser temperature.

- 45 In a well designed device, and if pressure and temperature are properly coordinated, the temperature of the entering water will be only four or five degrees below the discharging temperature of the refrigerant leaving the condenser, so that the arrangement shown in Fig. 2 is not only simple but accurate in its action.

- 50 If it be desired to control the system directly by the temperature of the refrigerant leaving the condenser, this can be effected in the manner shown in Fig. 3. In this case the cup 42 is not used, and hence may be omitted, as indicated in Fig. 3. Instead of plugging the opening 34, as shown in Fig. 2, the pipe 65 is connected to the opening 34 and terminates in a bulb 66 mounted in an enlargement 67 in the high pressure condensate line 59. An expansible fluid is confined in the bellows 29, pipe 65 and bulb 66 and develops a pressure in response to the temperature of the 60 high pressure condensate, the fundamental

principle of operation being identical with that shown in Fig. 2.

In Fig. 4 the evaporator 51, brine tank 52, and receiver suction trap 53 are identical with the similarly numbered parts of Fig. 2.

70 The section line 54 leads to the low pressure suction connection of a compressor 55^a. This compressor is of a known type having two suction inlets, one of which is connected to the suction connection 54 and operates at a relatively low suction pressure. The other is connected to an intermediate suction line 71 and operates to maintain a higher or so-called intermediate suction pressure.

75 As an example of such a compressor may be mentioned the type having an automatic inlet valve controlling the low pressure suction to the working space, which is open throughout the suction stroke, and a higher or intermediate pressure suction which leads through the cylinder walls and is controlled by the piston in such a way as to be open only at the end of the suction stroke. The suction connection 71 leads from the top of an intermediate receiver 72. The receiver 72 is connected to the receiver suction trap 53 by pipe 73 and flow is controlled by a valve 74 which is actuated by a float 75. The float 75 responds to a rise of liquid level in the receiver 72 to open the valve 74.

80 In the arrangement shown, the expansion of a portion of the refrigerant in the intermediate receiver 72, cools the remainder sufficiently to cause liquefaction.

85 The high pressure gas line is identical with that in Fig. 2, and is indicated by the numeral 56. The same is true of the condenser, which is numbered in the same way as in Fig. 2. The high pressure liquid line 59 leads from the lower end of the condenser to the valve body 11, as in Fig. 2. The low pressure liquid line 61 leads to the intermediate receiver 72 instead of leading to the receiver suction trap 53. In all cases the receiver suction trap is of sufficient volume to compensate for the varying pressure in the condenser and thus it serves as a reserve storage space for the refrigerant.

90 In Fig. 4 as in Fig. 2 the condenser cooling water passes through the cup 42, but in Fig. 4 the outflowing water. This arrangement is shown simply to illustrate the approximate equivalence of the two arrangements, but either arrangement may be used in Fig. 4 as in Fig. 2, or the substitute arrangement of Fig. 3 might be adopted in Fig. 4 in an obvious manner.

100 In any of the cases suggested an increase of condenser temperature or the occurrence of conditions which would produce an increase of condenser temperature (for example an increase in the temperature of the cooling water, in Fig. 2) will have the effect of producing an increase of condenser pressure. 105 The effect is automatically to increase the 110

heat transfer and consequently to neutralize at least partially the loss of refrigerative effect incident to the higher temperature of the refrigerant leaving the condenser.

5 By adopting a proper relation between the pressures acting downward through bellows 29 and upward through bellows 24, it is possible to establish regulative characteristics such as will cause the system as a whole to 10 maintain approximately the most desirable conditions.

The ratio of effective areas of the bellows 29 and bellows 24 determines the amount of super-pressure secured. Using ammonia as 15 the thermal fluid, a suitable ratio is about seven to one. Under such conditions, for each pound per square inch rise in bellows 29, condenser pressure must rise seven pounds per square inch.

20 While I have shown two specific refrigeration circuits, it is to be understood that these are intended to be illustrative and not limiting, and that other known circuits might be used. Furthermore, as explained, while the 25 invention is primarily intended for use with carbon-dioxide, it is useful with any refrigerant under conditions of use requiring condensation near the critical temperature, and particularly in cases where the critical temperature may be at times exceeded.

What is claimed is,—

1. The combination with a refrigerating system of the compressor condenser expander type, of a valve for throttling the outflow 35 from the condenser; means for passing cooling fluid in heat exchanging relation with the condenser; and thermally responsive motor means subject directly to the temperature of the cooling fluid leaving the condenser and operatively connected with said valve to close the same progressively as the temperature of the cooling fluid rises and so arranged that the valve is normally open and commences to close as the refrigerant 40 leaving the condenser approaches its critical temperature.

2. The combination with a refrigerating system of the compressor, condenser expander type, of a valve for throttling the outflow 50 of refrigerant from said condenser; an expansible chamber motor operatively connected with said valve; means for passing condenser cooling fluid in heat exchanging relation with said motor; and an expansible 55 fluid in said motor whose characteristics are such relatively to similar characteristics of the refrigerant that when the condensate approaches the critical temperature of the refrigerant said valve will commence to move in a closing direction.

3. The combination with a refrigerating system of the compressor condenser expander type, using a refrigerant whose critical temperature is at times approached and exceeded 65 by the temperature in the condenser, of a valve

for throttling the outflow from the condenser; motor means for actuating said valve comprising a thermally responsive element operating in accordance with the temperature of refrigerant discharging from the condenser, arranged to move said valve in a closing direction and operative at temperatures ranging from slightly below to above the critical temperature of the refrigerant; and a pressure motor of smaller effective area than said thermally responsive motor means subject to condenser pressure arranged to urge said valve in an opening direction.

4. The combination of a refrigerating system of the compressor condenser expander type, using a refrigerant whose critical temperature is at times approached and exceeded by the temperature in the condenser, of a valve for throttling the outflow of refrigerant from said condenser; an expansible chamber motor operatively connected with said valve, said motor containing a thermally expansible fluid and being in heat conducting relation with the outflowing refrigerant; and a pressure motor of smaller effective area than, and acting in opposition to the first named pressure motor and subject to condenser pressure.

5. The combination with a refrigerating system of the compressor condenser expander type, using a refrigerant whose critical temperature is at times exceeded by the temperature in the condenser, of a valve for throttling the outflow from the condenser; and thermally responsive motor means operative at temperatures at and above the critical temperature of said refrigerant and connected to actuate said valve, said connection being such that as temperature in the condenser approaches and rises above the critical the valve is moved in a closing direction to retain in the condenser a pressure which rises faster than condenser pressures would normally rise.

6. The combination with a refrigerating system of the compressor condenser expander type, of a valve for throttling the outflow from the condenser; means for passing cooling fluid in heat exchanging relation with the condenser; and thermally responsive motor means subject directly to the temperature of the cooling fluid approaching the condenser and operatively connected with said valve to close the same progressively as the temperature of the cooling fluid rises, the parts being so arranged that the valve is normally open and moves toward closed position as the refrigerant leaving the condenser rises in temperature, the range of such rise being near to and above the critical.

7. The combination with a refrigerating system of the compressor condenser expander type, the condenser being liquid cooled and the refrigerant being such that its critical temperature is at times approached or exceed-

- ed by the temperature of such cooling liquid, of a valve for throttling the outflow from the condenser; motor means for actuating said valve comprising a thermally responsive element subject to the temperature of said cooling liquid and arranged to move said valve in a closing direction as the temperature of the cooling liquid rises; and a pressure motor subject to condenser pressure, arranged to urge said valve in an opening direction, said thermally responsive motor means and the flow of cooling fluid being so coordinated that the motor starts to move said valve in a closing direction when refrigerant discharging from said condenser approaches its critical temperature.
8. The combination with a refrigerating system using a refrigerant whose critical temperature is at times exceeded by the temperature in the condenser, of a valve for throttling the outflow of refrigerant from the condenser; and a thermally responsive motor operative in a temperature range commencing below and extending above the critical temperature, said motor being connected to control said valve in such relation to temperature that as the temperature approaches the critical the valve is moved in a closing direction to retain in the condenser a pressure which rises faster than the normal condenser pressure would rise.
9. The combination with a refrigerating system, using a refrigerant whose critical temperature is at times exceeded by the temperature in the condenser, of a valve for throttling the outflow of refrigerant from the condenser; means for passing a cooling fluid in heat-exchanging relation with said condenser; and a thermally responsive motor subject directly to the temperature of such cooling fluid, and connected to close said valve as the temperature of the motor rises, said connection being such with reference to the differential between condenser temperature and cooling fluid temperature that as temperature in the condenser approaches the critical the valve is moved in a closing direction to retain in the condenser a pressure which rises faster than normal condenser pressure would rise.
10. The method of operating a refrigerating system of the type including a condenser in which the critical temperature of the refrigerant used is at times exceeded, which method comprises developing a secondary pressure as a result of the rise of condenser temperature in the ranges commencing substantially at the critical temperature and extending upward therefrom, and regulating the outflow from the condenser by the secondary pressure so developed in such manner that as condenser temperature rises above the critical, condenser pressure will increase at an abnormally rapid rate.
11. The method of operating a refrigerat-
- ing system of the type including a condenser in which the critical temperature of the refrigerant used is at times exceeded, which method consists in developing by thermodynamic means, a secondary pressure in accordance with condenser temperature and in the operative range from and above the critical temperature, regulating condenser pressure in response to the secondary pressure so developed, the regulation being such that as condenser temperature approaches and rises above the critical value, condenser pressure will rise at an abnormally rapid rate.
12. The method of operating a refrigerating system including a condenser in which the refrigerant at times exceeds the critical temperature, which consists in developing thermo-dynamically a pressure which varies in response to variations of condenser temperature, and in the operative range of the condenser, above the critical temperature, applying the pressure so developed, together with partial opposition by condenser pressure, to exercise a throttling control on the condenser, the regulation being such that as condenser temperature rises above the critical point, condenser pressure rises at an abnormally rapid rate.
- In testimony whereof I have signed my name to this specification.
- JOHN G. BERGDOLL.
